Patented Aug. 6, 1968

211,874

COMBINED BATHTUB SPOUT AND SOAP HOLDER

Paul A. Mongerson, Elyria, Ohio, assignor to Standard Screw Company, Hartford, Conn., a corporation of
New Jersey

Filed Dec. 20, 1967, Ser. No. 9,854

Term of patent 14 years

(Cl. D23—32)

FIGURE 1 is a front elevational view of a combined bathtub spout and soap holder showing my new design;

I claim:

The ornamental design for a combined bathtub spout and soap holder, as shown and described.
